UNITED STATES PATENT OFFICE.

MARY V. COLEMAN, OF ATLANTA, GEORGIA.

METHOD OF CUTTING AND FITTING GARMENTS.

SPECIFICATION forming part of Letters Patent No. 357,762, dated February 15, 1887.

Application filed March 9, 1886. Serial No. 194,671. (No model.)

To all whom it may concern:

Be it known that I, MARY V. COLEMAN, a citizen of the United States of America, residing at Atlanta, in the county of Fulton, and the State of Georgia, have invented certain new and useful Improvements in the Art or Method of Measurements for Cutting and Fitting Dresses and other Garments; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to a system of taking measurements for cutting out and fitting garments which is predicated upon the known proportions existing between the different parts of the human body, as will be hereinafter fully described.

In the accompanying drawings, Figure 1 is a diagram by which, one measurement being known, the others are determined and shown. Fig. 2 shows a pattern for a back of a basque drawn by measurements shown in Fig. 1. Fig. 3 is a pattern for the front of a basque drawn from measurements shown in Fig. 1. Fig. 4 is a pattern for a sleeve, also drawn from measurements shown in Fig. 1.

The rules of proportion applied to the human body demonstrate that one part of the body is in proportion to another throughout the entire structure. I have therefore devised a system by which I obtain from one measurement all the dimensions of the body that are necessary for cutting and fitting dresses. Those forms that appear to be different to these in their proportions are systematically so, and I have devised rules by which that difference can be ascertained and systematically provided for.

To reduce this method to practice I have devised the diagram Fig. 1, which is constructed in each case as follows:

From the point A is drawn a horizontal line, A J, perpendicular to which is drawn a line, A H. From the point of intersection A of the lines A J and A H is struck an arc, B C, the radius of which is the measurement around the

wrist between the wrist-joint and hand. With the length of the arc B C as a radius, strike the arc D E. Increase the radius of the arc D E by adding one-half of the radius of the arc B C and strike the arc F G. Draw a straight line, A K, from the point A that will bisect the angle and the arcs B C, D E, and F G at their centers. From the line A K, measure on the arc D E a distance equal to one-half the arc B C and strike the line M I parallel to the line A H.

In describing the manner of applying this system I will describe the method of laying out a plain basque for a lady, having what I will call, for convenience, a "normal" form, and afterward describe the method of ascertaining the proportions of those forms that are not normal. The length of the measurement around the wrist between the wrist-joint and hand being the fundamental measure, I divide it into six equal parts, each of which, for convenience, I will designate "one part." In stating the measurements for the following parts of the body, and afterward in explaining the manner of applying this system in marking out patterns for a front and back of a plain sack and a sleeve, as illustrations, I refer to the length of the lines in Fig. 1, which should be drawn in each case as above described. The smallest waist-size is B C increased by two parts, the next waist size is B C increased by three parts, the next waist-size is B C increased by four parts, and so on to the largest. I N is one-fourth of bust-measure. I N is one-fourth of hip-measure at the joint of pelvis-bone. M L is one-fourth of waist. M L is the length of shoulder. D E is the length of back. One-half of D E is the length under arm. One-half of D E plus B C is the length of inside of arm from the muscle to the wrist-joint. D E plus twice the length of B C plus three parts is the length of skirt. Three parts is length between waist and pelvis-bone.

The dimensions of various parts of the body, as above described, are sufficient for a guide in cutting the waist, sleeves, and skirt of a dress or similar garment. There is, however, a peculiarity of form in the shoulders of some people that it is necessary to take into account and provide for—namely, a sloping or drooping form from the neck to the arm.

To determine whether a form is square or droop shouldered, the person should drop the arm and bend the elbow to a right angle, observing the relative position of the forearm 5 near the elbow to the waist-line. If the bottom of the forearm is even with the waist-line, the shoulders may be classed as square. If the top of the forearm is even with the waist-line, the shoulders may be classed as drooping.

- 10 There are three positions which bodies occupy—namely, very erect, moderately erect, and stooping. For convenience I group these forms of back as follows: The erect form I will call the "first position," the moderately erect I 15 will call the "second position," and the form having the greatest amount of stoop I will call the "third position." The first position I call "normal." The second and third are abnormal.
- 20 In the diagrams, Figs. 2, 3, and 4, I assume that the form belongs to the first position. Fig. 2, being a diagram of the back of a plain basque, is made as follows: Draw a perpendicular line, $a z$, and measure from a on this 25 line the length of the arc $D E$, from which point measure at right angle one-third or two parts of the radius of the arc $B C$, which locates the corner b of the rectangle $a b c d$, the width of which is equal to $M L$. From c to e and from f to g is 30 two parts of wrist-measure, and from e to f and e to g is one-half of $D E$. $g h$ is one-half of $e g$. $a i$ is one-fourth of wrist-measure, or one and one-half part. Draw the line $i j$ parallel to $a b$. From h measure the length of the arc $M L$, 35 which is the shoulder-measure, letting it stop on the line $i j$ at the point of intersection k , from which point of intersection draw the line $k l$ parallel to the line $a d$ and intersecting the line $a b$. Draw the line $m n$ parallel to $a d$ and at a 40 distance from $b c e$ equal to the distance between the lines $a d$ and $l k$. $m n$ is the waist-line. Extend lines $a b$, $d c$, and $g e$ to meet line $m n$. The two parts of the wrist-measure $c e$ $f g$, which were added for the bust, must be 45 taken up in darts on the waist-line, as follows: Divide said waist-line into three equal parts, taking out one-third in center of back and remaining two at side body. The darts are represented by the letter o . Continue the line $f g$ 50 to p , which is one part added, and strike the line $p n$. This additional triangular piece, being taken from the front and added to the back, makes the waist more symmetrical. The point h will come to the top of the shoulder-joint. The curved mark for the armhole s 55 may be made to intersect the line $h k$ as far from the point h as fashion requires the seam to be from the shoulder-joint.

Fig. 3, being a diagram of the front of a 60 plain basque, is made as follows: Draw a perpendicular line, $a' z'$, and measure from a' on this line the length of the arc $D E$, from which point measure at a right angle one-third the radius of the arc $B C$, which locates the corner b' of the rectangle $a' b' c' d'$, which is the same 65 size as in Fig. 2. Draw the line $g' f'$ inter-

seeting at a right angle to and in the center of the line $c' d'$. From c' to e' is one-third of wrist-measure. Draw line $e' h'$ parallel to line $c' d'$. $p' q'$ is the one part taken off that 70 was added to the back. From f' to h' is one-half of e' to f' plus two parts or one-third of wrist-measure. Draw a line, $i' j'$, intersecting the line $a' d'$ at a point one-fourth plus one-sixth of the wrist-measure from a' and parallel 75 to the line $a' b'$. Draw a line from the point h' at such an angle, it being the length of the arc $M L$, Fig. 1, that it will exactly reach the line $i' j'$. Draw triangular addition $a' b' k'$. The distance from b' to k' , which is added for 80 bust and stomach, is one-sixth the radius of the arc $B C$. From a' to l' is one-half the radius of the arc $B C$. Measure one-half the distance from l' to k' , which is marked x' in Fig. 3. From x' to m' is one-third the radius 85 of arc $B C$, from which point draw the line for height of darts parallel to the waist-line. One-half the wrist-measure is taken up in darts, which are represented by the letter o' . If by observation it is decided that the line of the 90 waist goes up in front, the darts $o' o'$ must be taken up on the line $k' b' c' e'$; but if it droops or goes down, measure one part or one-sixth of the radius of the arc $B C$ from k' to s' and draw a line from that point to the point e' , which 95 becomes the waist-line and point of greatest width of darts.

Fig. 4, being a diagram of a sleeve, is made as follows: Draw a perpendicular line, $B' Z'$, and measure from B' on this line the length of 100 the arc $D E$ plus two parts, from which point measure at a right angle one-third the radius of the arc $B C$, which is the corner C' of the rectangle $A' B' C' D'$. The width of the rectangle is one-half the arc $B C$. From D' to E' 105 is one-third the radius of arc $B C$. From G' to H' is one-half of arc $D E$. The line $G' E'$ is drawn parallel to the line $A' D'$. The line $G' L'$ is drawn parallel to the line $E' C'$. From K' to H' is the length of the arc $B C$, and from 110 A' to H' is one-half the radius of arc $B C$. From H' to I' is the radius of arc $B C$ plus two parts. The line $H' I'$ is drawn at a right angle to the line $K' H'$. From E' to F' is one 115 part of the radius of arc $B C$. The triangular part $L' C' J'$ is added on the same principle and to the same width as the addition to waist. From M' to N' is the diameter of armhole in the back of waist. The under side of the sleeve is reduced in size by folding the pattern on the 120 lines $D' K'$ and $K' H'$, and by cutting as much inside this line as is found to be outside. By a little exercise of judgment the dotted lines are drawn in to make these patterns symmetrical and conform to the prevailing fashions. 125

If the pattern is being cut to fit a person with a square shoulder, it is drawn as shown in Figs. 2, 3, and 4; but if it is for a person with drooping shoulders the rectangle is drawn at an angle exactly the reverse as regards its position 130 to the lines $a z$, Fig. 2, $a' z'$, Fig. 3, and $B' Z'$, Fig. 4. If the position of the person to be

measured is that heretofore described as being the second position, instead of measuring one-third the radius of the arc B C to ascertain and locate the lower corner of the rectangle, measure one-fourth of the said radius; and if the person to be measured is of the form described as being the third position, use one-sixth of said radius for said measurement.

Having thus described my invention, what I to claim as new, and desire to secure by Letters Patent, is--

As an improvement in the art of dress cutting and fitting, a system in which the propor-

tions of the several parts are determined by means of a diagram consisting of arcs and sectoral lines, the proportionate lengths of which correspond with the known proportions of the body and are deduced from a single measurement, substantially as specified.

In testimony whereof I affix my signature in presence of two witnesses.

M. V. COLEMAN.
